MULTIPOST LIFT

Ion Von Kert Hott, Dayton, Ohio, assignor to The Joyce-Cridland Company, Dayton, Ohio, a corporation of Ohio

Application August 15, 1935, Serial No. 36,377

28 Claims. (Cl. 254—93)

This invention relates to a multi-post lift and is designed primarily for elevating a motor driven vehicle to permit access to be had to the underneath parts thereof for servicing the same. Some 5 motor vehicles are substantially heavier at one end than at the other, this being particularly true of busses and trucks and when such a vehicle is placed on a multi-post lift, that is, a lift having two or more lifting elements, the weight of 10 the load will be unequally distributed between the lifting elements with the result that one or more of the lifting elements will move at a greater speed than the other element or elements and the vehicle supporting structure will be 15 tilted, sometimes to a dangerous extent.

One object of the invention is to provide a multi-post lift with simple and efficient means for maintaining the load supporting structure in a substantially horizontal position, or substantially 20 at a predetermined angle to the horizontal, during the raising and lowering of the load regardless of the distribution of the weight of the load.

A further object of the invention is to provide 25 such a lift with means for positively preventing any appreciable tilting of the load supporting structure.

A further object of the invention is to provide 30 a multi-post lift with means for causing the lifting elements to move substantially in unison and for causing the distribution of the power to the several lifting elements in proportion to the loads thereon.

A further object of the invention is to provide 35 such a lift in which the excess power delivered to a lifting element having a relatively light load will be transferred to a lifting element having a heavier load.

Other objects of the invention will appear as 40 the mechanism is described in detail.

In the accompanying drawings Fig. 1 is a plan view of an automobile lift of the free wheel type embodying my invention and partly broken away; Fig. 2 is a side elevation of such a lift; Fig. 3 is 45 a vertical sectional view taken through the lifting element to which fluid is initially delivered and through a portion of one of the cross members; Fig. 4 is a vertical section of one of the other lifting elements, with a portion of the cross member in elevation; Fig. 5 is a section taken on the line 5—5 of Fig. 3; Fig. 6 is a section taken on the line 6—6 of Fig. 3; Fig. 7 is a section taken on the line 7—7 of Fig. 3, showing a portion of the cross member in plan; Fig. 8 is a section taken on the line 8—8 of Fig. 3; Fig. 9 is a

section taken on the line 9—9 of Fig. 8; Fig. 10 is a section taken on the line 10—10 of Fig. 8; Fig. 11 is a detail view of the cable clamp; Fig. 12 is a diagrammatic view showing the fluid connections between the several lifting elements; Fig. 13 is a diagrammatic view showing the arrangement of the controlling cable; Fig. 14 is a plan view of a portion of a lift of the runway type showing the invention applied thereto; Fig. 15 is a section taken on the line 15—15 of Fig. 10; Fig. 16 is a section taken on the line 16—16 of Fig. 14; Fig. 17 is a transverse section taken on the line 17—17 of Fig. 14; and Fig. 18 is a side elevation of a portion of a lift of the runway type.

In these drawings I have illustrated one embodiment of my invention, together with a minor modification thereof, and have shown the same as applied to a four post fluid operated automobile lift but it will be understood that this particular embodiment has been chosen for the purposes of illustration only, that the invention may take various forms and may be applied to lifts of various kinds comprising two or more lifting elements.

In the four post lift here illustrated the lifting elements, or posts, are arranged in pairs near the respective ends of the lift, the lifting elements 20 and 21 being arranged at one end of the lift and the lifting elements 22—23 being arranged at the other end of the lift. The movable parts of the lifting elements of the two pairs are connected one to the other by cross members 24 and 25 and these cross members are connected one to the other by longitudinal members 26 and 27. In the free wheel type of lift, as shown in Figs. 1 to 13, the longitudinal members 26 and 27 constitute the axle supporting rails of the lift and these rails and the cross members constitute the load supporting structure as a whole.

The mechanism as a whole is mounted above the supporting surface so that no excavation of any kind is necessary for the installation of the lift. The lifting elements may be of any suitable character but preferably they are fluid operated and, as here shown, each lifting element comprises a piston 28 which extends upwardly from a base 29 which is adapted to be mounted on and, if desired, rigidly secured to a suitable supporting surface, such as the floor or pavement of an automobile service station. Mounted on the piston 28 for vertical movement is a cylinder 30 which is closed at its upper end, as shown at 31, and is provided near its lower end with suitable packing 32 to prevent the escape of fluid between

the cylinder and the piston. The interior diameter of the cylinder is somewhat greater than the exterior diameter of the piston to provide a space through which the fluid may flow from one end 5 of the cylinder to the other. Arranged within the cylinder is a stop 33 adapted to engage a co-operating stop 34 at the upper end of the piston to limit the movement of the cylinder with relation to the piston. Stops 33 and 34 are in the 10 form of short segments, the lower segments 33 being spaced apart a distance greater than the width of the segments 34 so that by imparting a partial rotation to the cylinder the latter may be released and removed from the piston.

15 The cross bars 24 and 25 are connected with the movable members or cylinders of the respective lifting elements and may be secured thereto in any suitable manner. In the arrangement here shown a bracket 35 is rigidly secured to each 20 cylinder and extends laterally and downwardly therefrom, the inner end 36 of the bracket being shaped to fit about the end of the corresponding cross bar, to which it is rigidly secured, as by welding. The bracket 35 may be attached to the 25 cylinder in various ways and, in the construction shown, the outer portion of the bracket is curved to fit about the adjacent side of the cylinder and is provided on each side with lugs 37 and 38 arranged one above the other. The lugs 37 are 30 bolted or otherwise secured to cooperating lugs 40 carried by a band 41 which extends about the cylinder and is embraced by the bracket 35. The upper lugs 38 of the bracket are secured by bolts, or otherwise, to cooperating lugs 42 which are 35 welded directly to the cylinder. The cross members 24 and 25 may be of any suitable character but they must have sufficient strength to jointly support the load on the lift and inasmuch as the vehicle must be driven across one of these supporting members in order to place it in position above the rails 26 and 27 and is usually driven across the other supporting member in removing the same from the lift it is desirable that the cross members should be of a low construction and supported on or close to the supporting surface when the lift is in its lowered position. It is also desirable that the inner and outer walls of these cross members should be sloped to facilitate the movement of the wheels over the same. In the 45 present construction each cross member is substantially semi-circular in cross section, see Fig. 8, which not only provides it with the sloping surfaces but also provides within the same a channel which is utilized for a purpose which will be hereininafter explained. If desired, the cross member may be reinforced by a plate 43 arranged within the same and welded or otherwise secured to the respective side walls.

The longitudinal members 26 and 27 may be 50 secured to the cross members in any suitable manner but in the construction here shown the longitudinal members are in the form of H-bars and I have rigidly mounted brackets 44 on the cross bars, the brackets being preferably welded. 55 Each bracket has two projections 45 provided at their upper and lower edges with flanges 46 and spaced apart a distance slightly greater than the thickness of the web of the H-bar so that the projections may be inserted in the respective 60 channels of the H-bar as shown in Fig. 9. The vertical portion of each projection of the bracket is slotted longitudinally, as shown at 47, and a bolt 48 is passed through the slotted projections and through the web of the H-bar. This bolt 65 has a tapered head 49 which engages in the slot

of one projection and carries a tapered washer 50 which engages in the slot of the other projection, the slots being preferably countersunk to receive the head and washer. Thus by tightening down the bolt the two projections are not only clamped tightly against the web of the H-bar but they are expanded to force the flanges 46 into tight engagement with the upper and lower flanges of the H-bar.

Fluid under pressure may be delivered to the several lifting elements in any suitable manner but I prefer to deliver all the fluid initially to one lifting element and to distribute the same from that lifting element to the other lifting elements. Preferably a single supply pipe 51 leads 10 from a suitable source of supply of fluid under pressure, such as a reservoir 152, in which oil is stored under air pressure, to one of the lifting elements, in the present instance the element 20. This pipe extends upwardly through 15 the piston and discharges into the cylinder above the head of the piston. The lifting element 20 is connected with each of the other lifting elements to provide for the distribution of the fluid and, in the arrangement shown, cross conduits 52 20 connect the cylinders of the respective pairs of lifting elements and a longitudinal conduit 53 connects the two cross conduits 52. In this manner the cylinder of each lifting element is connected with the cylinder of each other lifting element. The conduits 52 are shown as terminating in Y-fittings 54 which extend partially about the respective cylinders and communicate therewith at separated points. When oil or other fluid is first delivered to the initial cylinder, of lift 20, it will flow downwardly between the cylinder and the piston and through the conduits 52 and 53 to the other cylinders and when all the cylinders have been once filled the delivery of additional fluid will exert substantially equal 30 pressure on the several cylinders and will tend to move the same upwardly in unison. After the cylinders have been once filled with fluid they will remain filled between successive operations and fluid admitted to the initial cylinder will immediately exert pressure on all the cylinders. If the load on one lifting element is lighter than the load on another lifting element the lifting element having the lighter load will tend to move at a greater speed than the lifting element having the heavier load, thus causing the tilting of the load supporting structure, and I have therefore provided means for controlling the relative movement of the lifting elements and for causing the fluid to be distributed in proportion to the 35 load on the several lifting elements.

For the purpose of so controlling the relative movements of the lifting elements and the distribution of power I have provided an auxiliary stop device which is connected with the several lifting elements and the movement of which is so controlled as to cause said lifting elements to move in substantial unison. This stop device 40 preferably consists of one or more flexible members which may be of any suitable character and it is herein referred to as a cable. In the preferred construction a single endless cable is connected with each lifting element and its longitudinal movement is so controlled as to cause the lifting elements to move in substantial unison. In the construction shown each lifting element has secured thereto, near its upper end, a guide, such as a pulley 55, and has secured thereto, near its lower end, two guides, such as pulleys 56 and 57, the lower guides being arranged 45

in planes transverse to the plane of the upper guide. Other guides 60 are mounted on the cross members 24 and 25 between the ends of the same. A cable 58 is threaded about the several guides on the lifting elements and on the cross members and has its ends connected one to the other so that in operation it constitutes an endless cable. The means for connecting the ends of the cable is preferably of such a character that the cable may be drawn taut and its tension regulated, such, for example, as a turn buckle 59. This arrangement of the cable provides the same, adjacent to each lifting element, with an upwardly extending portion which is looped about the upper guide 55. The two sides of the looped portion of the cable extend about the respective lower guides 56 and 57 and the intermediate portions of the cable are carried through the channeled cross bars 24 and 25 and the channeled longitudinal members 26 and 27 to the lower guides of the other lifting elements. One side of each looped portion of the cable is held against movement, as by anchoring the same to an upright stationary standard 60 which, as shown in Fig. 3, is mounted on the base 29 which carries the piston 28. In the present arrangement, the anchoring means comprises an arm 61 rigidly secured to the standard 60 and having a hook-shaped portion 62 to receive the cable. A clamping member 63 is connected with the arm 61 by means of a screw 64 which forces the same into firm engagement with the cable. As the lifting elements move upwardly in unison the lower guides will approach the respective anchors 61 and the upper guides will move away from those anchors, thus extending the loops of the cable above the respective anchors. This upward extension of the loop is permitted by the feeding of the lower portion of the anchored side of each cable loop to the unanchored side of another cable loop and therefore one lifting element cannot move with a speed greater than the speed at which the other lifting element moves. For example, when the lifting elements 21 and 23 are moving upwardly that portion of the anchored side of the cable loop of lifting element 23 which passes about the guide 56 will be fed about the guides on the cross members and about the lower guide 57 of the lifting element 21 so as to supply additional cable to the loop of lifting element 21 and permit the upper guide of that element to move upwardly, but obviously the lifting element 21 can move no faster than the cable is supplied to it from the lifting element 23 and therefore the two lifting elements will move at the same speed. If lifting element 21 carries a lighter load than the lifting element 23 it will tend to move at a greater speed than the lifting element 23, due to the fact that fluid power is normally supplied to the two lifting elements in equal amounts, but the cable will prevent the lifting element 21 moving at greater speed than the lifting element 23 and the excess fluid which is delivered to the lifting element 21 will be transferred through the conduits 52 and 53 to the lifting element 23, thereby supplying that lifting element with additional power to elevate its heavier load.

The cable will operate in a similar manner to cause the several lifting elements to move downwardly substantially in unison when the load is being lowered. The lowering of the lifting elements is effected by the weight of the loads thereon and the heavier load on the lifting element 23, in the example above used, will tend

to cause the same to move downwardly at a greater speed than the lifting element 21 which carries the lighter load, but during this downward movement the cable 58 is moving in a direction reverse to that above described and it is fed from the loop portion of the lifting element 21 to the anchored portion of the cable loop of lifting element 23. The lower guides of the lifting element 23 are supported by the cable and therefore that lifting element can move only as fast as the cable is fed from the lifting element 21 to the anchored portion of the cable loop of lifting element 23. In this manner the movement of each lifting element is controlled by the movements of the other lifting elements and when the cable is properly adjusted none of the lifting elements can have movement with relation to the others. Any relative movement of the lifting elements which may result from slack in the cable or otherwise, will be so slight that it will cause no substantial tilting of the load supporting structure. In an installation in which the load supporting structure is normally inclined it will be retained at the predetermined angle throughout the operation of the lift.

When the invention is applied to a lift of the runway type, that is, to a lift which is provided with tracks or runways onto which the wheels of the vehicle are driven, the only change necessary is supplying the load supporting structure with runways instead of with axle supporting rails. If desired, the longitudinal members 26 and 27 may be retained and the runways mounted on the cross members 24 and 25. However, in the interest of economy and to eliminate unnecessary obstructions beneath the vehicle I prefer that the runways should themselves constitute longitudinal connecting members, thereby enabling the connecting members 26 and 27 to be dispensed with. The load supporting structure is, of course, provided with two runways, one near each side thereof, and in Figs. 14 and 18 I have shown only one of the two runways. As there illustrated the runway 65 is supported at its respective ends on the cross members 24 and 25 and it is provided with a longitudinal reinforcing bar 66, secured at its lower side, which is rigidly secured at its respective ends to brackets 67 rigidly secured to the cross members, by welding or otherwise, as shown in Fig. 16. In the present instance, the reinforcing member 66 is arranged near one side of the runway and, if desired, the other side of the runway may be secured directly to the cross members, as by means of brackets 68 rigidly secured to the cross members. The reinforcing member 66, is here shown as Z-shaped in cross section and thus provides a channel to receive the longitudinal stretch of the cable 58 and the longitudinal conduit 53. Usually the runway is provided at its respective ends with ramps 69 to facilitate the movement of the vehicle onto the same.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. In a multi-post lift comprising at least two lifting elements spaced one from the other, a load supporting structure carried by said lifting elements, and means for supplying power to said lifting elements, a device for preventing the rel-

- ative movement of said lifting elements including controlling means having parts connected with the respective lifting elements for bodily movement with relation thereto, and means supported independently of said lifting elements and cooperating therewith to control the movement of said controlling means with relation to said lifting elements.
2. In a multi-post lift comprising at least two lifting elements spaced one from the other, a load supporting structure carried by said lifting elements, and means for supplying power to said lifting elements, flexible means connected with said two lifting elements for longitudinal movement with relation thereto and controlled in accordance with the loads on the respective lifting elements to prevent one lifting element from moving a greater distance than the other lifting element moves.
- 20 3. In a multi-post lift comprising at least two lifting elements spaced one from the other, a load supporting structure carried by said lifting elements, and means for supplying power to said lifting elements, flexible means connected with said two lifting elements for longitudinal movement with relation thereto and controlled in accordance with the loads on the respective lifting elements to prevent a lifting element having a lighter load from moving a greater distance than a lifting element having a heavier load and to cause excess power supplied to the lifting element having the lighter load to be diverted to the lifting element having the heavier load.
- 25 4. In a multi-post lift comprising at least two lifting elements spaced one from the other, a load supporting structure carried by said lifting elements, and means for supplying power to said lifting elements, a cable extending between said two lifting elements, means adjacent to each lifting element for anchoring said cable to a stationary part, and guides connected with said lifting elements for movement therewith and engaging said cable between the anchored portions thereof, said guides being so arranged with relation to said anchoring means as to cause the two lifting elements to move substantially in unison.
- 30 5. In a multi-post lift comprising at least two lifting elements spaced one from the other, a load supporting structure carried by said lifting elements, and means for supplying power to said lifting elements, a cable extending between said two lifting elements, means adjacent to each lifting element for anchoring said cable to a stationary part, and guides connected with said lifting elements for movement therewith and engaging said cable between the anchored portions thereof, one of said guides being arranged above the anchoring means adjacent to one lifting element and another of said guides being arranged below the anchoring means adjacent to the other lifting element, whereby the first mentioned guide can move upwardly no faster than the last mentioned guide moves upwardly.
- 35 6. In a multi-post lift, a plurality of lifting elements, a load supporting structure carried by said lifting elements, means for supplying power to said lifting elements, upper and lower guides connected with one of said lifting elements for movement therewith, a lower guide connected with the second lifting element for movement therewith, a cable having a portion looped about the upper guide of the first mentioned lifting element, means for anchoring one side of said cable at a point below said upper guide, the other
- 40 side of said cable extending about the lower guides of both lifting elements, and means for anchoring said cable at a point above the lower guide of said second lifting element.
- 45 7. In a multi-post lift, a plurality of lifting elements, a load supporting structure carried by said lifting elements, means for supplying power to said lifting elements, upper and lower guides connected with the respective lifting elements for movement therewith, and a flexible controlling device comprising a plurality of sections, each section being anchored to a stationary part adjacent to one of said lifting elements, extending upwardly from its anchor about the upper guide of that lifting element, then downwardly and about the lower guide of that lifting element, thence about the lower guide of another lifting element and being anchored to a stationary part above the last mentioned guide.
- 50 8. In a multi-post lift, a plurality of lifting elements, a load supporting structure carried by said lifting elements, means for supplying power to said lifting elements, guides connected with said lifting elements for movement therewith, a flexible controlling device having portions extending about the respective guides and movable therewith, and means for holding said flexible device against bodily movement in the direction of its length.
- 55 9. In a multi-post lift comprising four lifting elements arranged at the corners of a rectangular figure, a load supporting structure carried by said lifting elements, and means for supplying power to said lifting elements, a flexible device having parts connected with the respective lifting elements for movement therewith, and means to control the movements of said parts of said flexible device to prevent one lifting element being moved a greater distance than another lifting element is moved.
- 60 10. In a multi-post lift, a plurality of separately movable lifting elements, a load supporting structure carried by said lifting elements, means for supplying power simultaneously to said lifting elements, a single cable connected with all of said lifting elements for movement thereby in the direction of its length, means for automatically controlling the movement of the cable to cause the same to retard the movement of any lifting element which tends to move at a greater speed than another lifting element, and means for so connecting said power applying means with said lifting elements that excess power will be diverted from said retarded lifting element to said other lifting element.
- 65 11. In a multi-post lift, a plurality of fluid operated lifting elements, a load supporting structure carried by said lifting elements, fluid conduits connecting said lifting elements one with the other, means for supplying fluid under pressure from a source of fluid supply to one only of said lifting elements, and means for causing said fluid to be distributed from said one lifting element to the other lifting elements in proportion to the loads on the several lifting elements.
- 70 12. In a multi-post lift, a plurality of fluid operated lifting elements, a load supporting structure carried by said lifting elements, means for normally supplying fluid under pressure to said lifting elements, guides carried by and movable with the respective lifting elements, a single cable extending about a plurality of said guides and movable thereon by the movement of said lifting elements, and means for controlling the movement of said cable to cause the same to act

on said guides to cause the lifting elements with which said guides are connected to move in unison.

13. In a multi-post lift, a plurality of fluid operated lifting elements, a load supporting structure carried by said lifting elements, means for normally supplying fluid under pressure to said lifting elements, guides carried by and movable with the respective lifting elements, an endless cable extending about a plurality of said guides, and means for controlling the movement of said cable to cause the lifting elements with which it is connected to move in unison.

14. In a multi-post lift, a plurality of fluid operated lifting elements, a load supporting structure carried by said lifting elements, means for normally supplying fluid under pressure to said lifting elements, guides carried by and movable with the respective lifting elements, an endless cable extending tautly about a plurality of said guides, portions of said cable being movable on said guides by the movement of said lifting elements, and means for holding other portions of said cable against movement.

15. In a multi-post lift, a plurality of fluid operated lifting elements, a load supporting structure carried by said lifting elements, means for supplying fluid under pressure to said lifting elements and for diverting portions of said fluid from one lifting element to another lifting element, guides carried by and movable with the respective lifting elements, a single cable extending about a plurality of said guides and movable thereon by the movement of said lifting elements, and means for controlling the movement of said cable to cause the same to so act on the lifting elements with which said guides are connected as to retard the movement of any of said lifting elements which tends to move at a greater speed within another of said lifting elements and to cause fluid to be diverted from the retarded lifting element to the other lifting element.

16. In a multi-post lift, four fluid operated lifting elements arranged at the corners of a rectangular figure, a load supporting structure carried by said lifting elements, means for supplying fluid under pressure to said lifting elements normally in substantially equal amounts and for diverting portions of said fluid from one lifting element to another lifting element, a guide carried by and movable with each lifting element, a single cable extending about all four of said guides and movable thereon by the movement of said lifting elements, and means for controlling the movement of said cable to cause the same to retard the movement of any of said lifting elements which tends to move at a greater speed than another of said lifting elements and to cause fluid to be diverted from the retarded lifting element to said other lifting element.

17. In a multi-post lift, four fluid operated lifting elements arranged at the corners of a rectangular figure, a load supporting structure carried by said lifting elements, means for supplying fluid under pressure to said lifting elements normally in substantially equal amounts and for diverting portions of said fluid from one lifting element to another lifting element, a guide carried by and movable with each lifting element, an endless cable extending about all four of said guides, portions of said cable being movable on said guides by the movement of said lifting elements, and means for holding other portions of said cable against movement.

18. In a multi-post lift, a plurality of separately movable lifting elements, a load supporting struc-

ture carried by said lifting elements, means for supplying power simultaneously to said lifting elements, guides carried by the respective lifting elements, a cable extending about said guides, and means for controlling the movement of said cable to cause it to resist the movement of one lifting element with relation to another lifting element.

19. In a multi-post lift, a plurality of separately movable lifting elements, a load supporting structure carried by said lifting elements, means for supplying power simultaneously to said lifting elements, a guide carried by each lifting element, a cable carried by said lifting elements and having portions looped about the respective guides, and means for holding one side of each looped portion of said cable against movement.

20. In a multi-post lift, a plurality of separately movable lifting elements, a load supporting structure carried by said lifting elements, means for supplying power simultaneously to said lifting elements, an upper guide and a pair of lower guides carried by each lifting element, a cable having portions looped about the respective upper guides, each side of each looped portion of said cable extending about one of the lower guides of that lifting element to the lower guide of another lifting element, a stationary member adjacent to each lifting element, and means for anchoring one side of each looped portion of said cable to one of said stationary members.

21. In a multi-post lift, a plurality of fluid operated lifting elements, a load supporting structure carried by said lifting elements, fluid conduits connecting said lifting elements one with the other, means for supplying fluid under pressure from a source of fluid supply to one of said lifting elements, an upper guide and a pair of lower guides carried by each lifting element, a cable having portions looped about the upper guides of the respective lifting elements, each side of each looped portion of said cable extending about a lower guide of its lifting element to the lower guide of another lifting element, a stationary member adjacent to each lifting element, and means for anchoring one side of each looped portion of said cable to one of said stationary members.

22. In a multi-post lift, a plurality of stationary upright pistons, a cylinder mounted on each piston for vertical movement with relation thereto, a load supporting structure carried by said cylinders, means for supplying fluid under pressure to one only of said cylinders, conduits movable with said cylinders to conduct fluid from one conduits connecting said lifting elements one with said cylinders to automatically retard the movement of any cylinder which tends to move at a greater speed than another cylinder and to cause fluid to flow from the retarded cylinder to said other cylinder.

23. In a multi-post lift, two pairs of fluid operated lifting elements arranged near the respective ends of said lift, a load supporting structure carried by said lifting elements, conduits connecting the lifting elements of each pair one with the other and with the lifting elements of the other pair, means for supplying fluid under pressure to one only of said lifting elements, a single cable connected with the several lifting elements and movable therewith, and means for controlling the movement of said cable to cause it to retard the movement of any of said lifting elements which tends to move at greater speed than another of said lifting elements.

24. In a multi-post lift, two pairs of stationary pistons extending upwardly from a supporting surface near the respective ends of said lift, cylinders mounted on the respective pistons for 5 vertical movement with relation thereto, cross members connecting the lower ends of the cylinders of the respective pairs and arranged to be located close to said supporting surface when said cylinders are in their lowermost positions, a longitudinal member connecting said cross members, conduits connecting the cylinders of each pair one with the other and with the cylinders of the other pair, means for supplying fluid under pressure to said cylinders, a single cable 10 connected with all of said cylinders and movable therewith, and means for controlling the lengthwise movement of said cable to cause the same to retard the movement of any cylinder which tends to move at a greater speed than another cylinder. 15
25. In a multi-post lift, two pairs of stationary pistons extending upwardly from a supporting surface near the respective ends of said lift, cylinders mounted on the respective pistons for vertical movement with relation thereto, cross members connecting the cylinders of the respective pairs and arranged to be located close to 20 said supporting surface when said cylinders are in their lowermost positions, a longitudinal member connecting said cross members, said members having longitudinal channels, conduits extending through said channels and connecting said cylinders one with the other, a cable 25 extending through said channels and having portions connected with the respective cylinders, and means for controlling the longitudinal movement of said cable to cause the same to retard the movement of any cylinder which tends to move at a greater speed than another cylinder. 30
26. In a multi-post lift, two pairs of stationary pistons extending upwardly from a supporting surface near the respective ends of said lift, cylinders mounted on the respective pistons for vertical movement with relation thereto, cross members connecting the cylinders of the respective 35 pairs and arranged to be located close to said supporting surface when said cylinders are in their lowermost positions, a longitudinal member connecting said cross members, conduits connecting the cylinders of each pair one with the other and with the cylinders of the other pair, means for supplying fluid under pressure to said cylinders, an upper guide and two lower guides carried by each cylinder, other guides carried by said cross members, an endless cable extending about 40 the upper and lower guides of each cylinder and 45 about the guides of said cross members, a stationary member adjacent to each cylinder, and means for rigidly connecting said cable with each stationary member. 50
27. In a multi-post lift, two pairs of stationary pistons extending upwardly from a supporting surface near the respective ends of said lift, cylinders mounted on the respective pistons for vertical movement with relation thereto, a bracket secured to the lower portion of each cylinder, channeled cross members secured to the brackets of the respective pairs of cylinders, a longitudinal member secured to said cross members, conduits extending through said channeled cross members and connected with the respective cylinders, a longitudinal conduit connecting the first mentioned conduits, means for supplying fluid under pressure to said cylinders, an upper guide and two lower guides carried by each cylinder, other guides carried by said cross members, an endless cable extending about the upper and lower guides on said cylinders and about the guides on said cross members, the transverse portions of said cable extending through the respective cross members, and means adjacent to each cylinder 55 to hold a portion of said cable against lengthwise movement. 60
28. In a multi-post lift, two pairs of stationary pistons extending upwardly from a supporting surface near the respective ends of said lift, cylinders mounted on the respective pistons for vertical movement with relation thereto, a bracket secured to the lower portion of each cylinder, channeled cross members secured to the brackets of the respective pairs of cylinders, a channeled longitudinal member extending between said cross members, a bracket secured to each cross member and having an expandable portion extending into the adjacent end of said longitudinal member, means for expanding said portions of 65 said brackets and securing the same to said longitudinal member, conduits extending through said cross members and connected with the respective cylinders, a conduit extending through said longitudinal member and connected with the first mentioned conduits, means for supplying fluid under pressure to said cylinders, upper and lower guides carried by each cylinder, other guides carried by said cross members, an endless cable extending through said channeled members and about the several guides, and means for holding a portion of said cable near each cylinder 70 against lengthwise movement. 75
